(57) **CLAIM**

The ornamental design for a scouring article, as shown and described.

DESCRIPTION

The file of this patent contains at least drawing/photograph executed in color. Copies of this patent with color drawings (s)/photograph(s) will be provided by the Office upon request and payment of the necessary fee.

FIG. 1 is a perspective view of a scouring article showing our new design;

FIG. 2 is a top view thereof;

FIG. 3 is a bottom view thereof;

FIG. 4 is a front view thereof, the rear view being a mirror image thereof; and,

FIG. 5 is a left side view thereof, the right side view being a mirror image thereof.

1 Claim, 1 Drawing Sheet

(1 of 1 Drawing Sheet(s) Filed in Color)
